UNITED STATES PATENT OFFICE.

ADOLF FRIEDRICH DRÖSSEL, OF MANNHEIM, GERMANY, ASSIGNOR TO THE CORPORATION OF FRITZ NEUMEYER AKTIENGESELLSCHAFT, OF NUREMBERG, GERMANY.

MOLD FOR THE CASTING ON OF SHAFTS FOR TWIST DRILLS AND SIMILAR TOOLS.

Application filed August 29, 1921. Serial No. 496,454.

To all whom it may concern:

Be it known that I, ADOLF FRIEDRICH DRÖSSEL, engineer, a citizen of the German Republic, and resident at Mannheim, Germany, with the post-office address Collini-strasse 31, have invented certain new and useful Improvements in Molds for the Casting on of Shafts for Twist Drills and Similar Tools (for which I have filed application in Germany, March 6th, 1920); and I do hereby declare the following to be a full, clear, and exact description of the invention, such as will enable others skilled in the art to which it appertains to make and use the same.

This invention relates to a mold with centering device designed for providing twist drills, especially broken twist drills with a cast-on shaft.

In order that the invention may be clearly understood, I shall proceed to describe the same with reference to the forms of construction shown by way of example on the accompanying drawing, wherein:—

Fig. 1 shows the first form of construction in longitudinal section.

Fig. 2 is a plan view of Fig. 1.

Fig. 3 is a longitudinal section through a mold of the second form of construction.

9 is the casting mold made in one piece which forms a thick-walled, jointless, cylindrical hollow body whose inner space 10 corresponds exactly with the shape of the drill shaft to be produced and to be cast-on.

Fig. 1 shows a conical inner space.

The centering device is formed by a disk 11 and by the centering sleeve 12. The centering sleeve 12 and the disk 11 are exactly con-axial with the casting mold 9. The disk 40 joins the end face of the casting mold and it is provided with a ring flange 13 having a thread 14, so that the two parts can be easily and securely connected the one with the other and that no metal can flow out between the surfaces of the casting mold and of the disk which join one another tightly. For drilling tools whose shapes differ very much, the disk and the casting mold are dimensioned correspondingly. As 50 the shaft of reamer bits and similar tools are often flattened at the free end to form a spike a corresponding cavity 15 is arranged in the casting mold in a disk 16 which closes the inner space 10. A filling

ring 17 serves as funnel for pouring in the 55 liquid metal.

The centering sleeve is rigidly but removably connected with the disk 11 by a thread 18 so that it can be exchanged for a centering sleeve of other inner width. The sleeve 60 12 has two opposite slits 19. A clamping ring 20 with two clamping screws for securing the centered tool in its position is placed upon the sleeve 12.

The remainder of the tool 22 is inserted 65 in the manner shown by the drawing into the centering device whereupon the casting mold is connected with said centering device, the funnel 17 put in place and the liquid metal poured in. All the parts of the 70 device consist each of a single body, and they can be turned on the lathe and bored exactly con-axially without difficulty and with absolute security.

The form of construction which has just 75 been described requires a special casting mold with a cylindrical hollow space if a cylindrical shaft has to be cast on.

The second form of construction of the casting mold shown on Fig. 3 permits to 80 use one and the same casting mold 9' for the casting on of conical and of cylindrical shafts. With this object in view an insertion sleeve 23 with conical outer surface and cylindrical boring is provided. When the 85 sleeve 23 is removed from the casting mold 9' a conical shaft can be produced and when the sleeve is inserted a cylindrical shaft can be produced. The boring of sleeve 23 could be conical, in which case the boring of the 90 casting mold ought to be cylindrical.

In order to enable that with one and the same device tools can be treated whose shapes differ more, the centering plate 15' (Fig. 5) has a lower boring which is larger 95 than the outer diameter of a separate centering sleeve 12'. The interval between the boring and the centering sleeve 12' is filled by an auxiliary sleeve 24 with flange 25. This centering sleeve has a flange 26. This flange serves on the one hand to tightly pack the contact surface of the casting mold 9' and of the flange 26 of the sleeve and on the other hand for securing the sleeve 100 in the position which it adopts when the disk 11' is screwed upon the casting mold 9'. If now a drill of larger size has to be repaired the auxiliary sleeve 24 and the 105

centering sleeve 12' are removed from plate 11' and a wider centering sleeve is inserted instead in the disk. Insertion sleeves 23 of various diameters and with various borings 5 can be inserted in the casting mold 9' so that one and the same casting mold can be used for tools of different sizes.

A convenient alloy consists of zinc 90%, aluminium 3%, copper 2% and of 5% of 10 approximately equal parts of antimony, lead and tin.

Claims:

1. An improved casting mold for the casting on of shafts of twist drills or similar 15 tools, comprising in combination a casting mold having a cylindrical bore, a centering device for the drill also having a cylindrical bore and means for rigidly but removably connecting the two parts.

2. An improved casting mold for the casting on of shafts of twist drills or similar tools, comprising in combination a cylindrical case which encloses the mold for the shaft, a disk with screw threads to be 20 screwed upon said cylindrical case, and a centering sleeve connected with said disk.

3. An improved casting mold for the casting on of shafts of twist drills or similar tools, comprising in combination a cylindrical case which encloses the mold for the shaft, a disk with screw threads to be 30 screwed upon said cylindrical case, and a centering sleeve removably connected with said disk by a screw thread.

4. An improved casting mold for the casting on of shafts of twist drills or similar tools, comprising in combination a cylindrical case which encloses the mold for the shaft, a disk with screw threads to be 35 screwed upon said cylindrical case, a slotted centering sleeve connected with said disk, and a clamping device for compressing the two halves of said centering sleeve separated by said slit.

5. An improved casting mold for the casting on of shafts of twist drills or similar tools, comprising in combination a cylindrical body enclosing the mold for the shaft, a disk with centering sleeve positioned at one end of said mold and a disk adapted to 50 be eccentrically placed upon the other end of the casting mold and provided at its center with a rectangular opening.

6. An improved casting mold for the casting on of shafts of twist drills or similar 55 tools, comprising in combination a casting mold having a cylindrical bore, a centering device for the drill also having a cylindrical bore, means for rigidly but removably connecting the two parts, and a filling ring 60 serving as funnel for pouring in the liquid metal connected with said casting mold.

7. An improved casting mold for the casting on of shafts of twist drills or similar tools, comprising in combination a casting 65 mold having a cylindrical bore, a centering device for the drill also having a cylindrical bore, means for rigidly but removably connecting the two parts, and an insertion sleeve 70 to be inserted in said casting mold.

8. An improved casting mold for the casting on of shafts of twist drills or similar tools, comprising in combination, a casting mold having a cylindrical bore, a removable base for said mold, a circular opening 75 through said base concentric with the bore of said mold, a centering device also provided with a cylindrical bore adapted to be positioned and secured within said concentric opening of the base and an auxiliary 80 annular sleeve interposed between said centering device and base.

In testimony whereof I affix my signature.

ADOLF FRIEDRICH DRÖSSEL.
